UNITED STATES PATENT OFFICE.

EDWARD D. BLACKWELL, OF MONTPELIER, VERMONT.

WRITING-PEN.

SPECIFICATION forming part of Letters Patent No. 256,958, dated April 25, 1882.

Application filed December 28, 1881. (Model.)

To all whom it may concern:

Be it known that I, EDWARD D. BLACKWELL, of Montpelier, in the county of Washington and State of Vermont, have invented 5 a certain new and useful Improvement in Writing-Pens, of which the following is a full, clear, and exact description.

The invention consists in a pen for writing purposes, constructed or provided in the hollow or concave inner side of its body with a cross wall or partition, preferably bowed and set inclining or shelving forward on its inner face, but which may be otherwise arranged, and of any suitable shape. This cross wall or 15 partition, while it has other functions or uses, is primarily for the purpose of preventing the ink in the pen from soiling the writer's fingers, as hereinafter described.

The invention is applicable to all or most 20 descriptions of pens, without regard to the material of which they are made, but is more particularly designed for steel or other metal pens requiring holders for their use.

Reference is to be had to the accompanying 25 drawings, forming part of this specification, in which similar letters of reference indicate corresponding parts in both the figures.

Figure 1 represents an inner face view of 30 a pen having my invention applied, and Fig. 2 is a longitudinal section of the same on the line xx in Fig. 1.

The pen, which may be of any desired pattern, has the hollow or inner concave side of its body a divided by a cross wall or partition, 35 b , at a suitable point in the length of the body to prevent interference with the fit of the pen in a suitable holder, and to avoid impairing the elasticity or flexibility of the pen. This wall b not merely strengthens the pen and 40 strains it from splitting without encumbering it or marring its beauty, but acts as a stop or dam to the ink contained within the pen from soiling the writer's or user's fingers. Thus, with the ordinary construction of pen, it is 45 often or almost invariably the case that when a pen-holder with ink in the pen is laid down or placed behind the ear the ink runs back

out of the pen onto the holder, especially when the latter is a rubber one, thereby causing the writer's fingers to be soiled with ink 50 when taking up the pen again for use. This is obviated by my improvement, the cross wall or partition b preventing the ink from running back out of the pen when the pen-holder is transposed, as described. Consequently the ink 55 does not pass onto the holder to subsequently soil the writer's fingers. To more effectually restrain the ink from running back out of the pen, as just referred to, it is preferred to make the partition b of a hollow or bowed form on 60 its face, and to set said face inclining or shelving forward—that is, toward the point of the pen, from the interior of the body of the latter—thus forming a guard or bucket to catch and hold any ink that may run back. Said wall or partition, however, which may either be formed with the pen in the course of its manufacture or be subsequently inserted in and secured to the pen, may be of any other suitable shape, 65 and be otherwise set or arranged.

Having thus fully described my invention, I claim as new and desire to secure by Letters Patent—

1. An improved pen having a wall or partition extending entirely across and rigidly attached to the inner concave side of its body, substantially as shown and described, whereby the ink is prevented from flowing back and soiling the fingers of the writer, and the pen strengthened and prevented from splitting, as 75 set forth.

2. A pen having the hollow or concave inner side of its body provided with a cross wall or partition of hollow form on its face and set inclining or shelving toward the point of the pen 85 from the interior of the body of the latter, whereby a bucket-shaped guard is formed within said body to catch and hold any ink running back within it, substantially as herein set forth.

EDWARD DICKINSON BLACKWELL.
